INTERNAL COMBUSTION ENGINE PISTON

Philip S. Webster, Muskegon, Mich.

Application March 19, 1942, Serial No. 435,272

4 Claims. (Cl. 309—15)

The present invention relates to an internal combustion engine piston and more particularly to a flexible piston for use in such an engine.

The primary objects of the instant invention are to provide a piston of the general character above indicated which is particularly well adapted for use in motors operated by low grade fuels; to provide such a piston whereby the thermodynamic efficiency of the motor is increased; to provide such a piston whereby a constant maximum combustion pressure is maintained during varying speed and load conditions of the working stroke of the piston and a more complete scavenging action is effected during its exhaust stroke; to provide such a piston wherein relatively little heat is transferred from the combustion head of the piston to its piston pin; to provide such a piston wherein a free circulation of air and oil vapors between the combustion head of the piston and its piston pin is permitted; to provide such a piston wherein its combustion head remains concentric with its cylinder wall at all times, dissipating its heat uniformly to the piston rings, thereby maintaining a better seal and a minimum amount of blow-by; to provide such a piston wherein there is no piston ring scoring of the cylinder wall frequently resulting in other types of pistons in instances wherein a piston slap develops as the result of a freezing action of the piston pin; to provide such a piston wherein detonation is prevented but otherwise results in instances wherein the gas fails to expand when the critical pressure of the fuel used is reached; to provide such a piston whose use in an internal combustion engine makes for more economical operation; to provide such a piston whose use permits of relatively higher compression ratios than are possible in instances of other type internal combustion engines using standard grade fuels; and, to provide such a piston which is reasonably light in weight, highly efficient in use and is economical in manufacture.

An illustrative embodiment of the invention is shown in the accompanying drawings, wherein:

Figure 1 is a vertical central sectional view of the piston on lines 1—1 of Figures 2 and 4;

Figure 2 is a fragmentary top plan view thereof;

Figure 3 is a side elevational view;

Figure 4 is a sectional view on line 4—4 of

Figure 3;

Figure 5 is a vertical central sectional view on line 5—5 of Figure 3;

Figure 6 is a sectional view thereof on line 6—6 of Figure 5;

Figure 7 is a sectional view on line 7—7 of Figure 5; and

Figure 8 is a perspective view of the member which secures the flexible piston head to its piston pin carrying base.

Referring then to the drawings wherein like parts of the structure shown are each designated by the same numerals in the several views, the vertically flexible or axially expansible-contractible piston there shown generally comprises an upper portion or combustion head 10, a lower portion 11 carrying a wrist pin 12, a central connecting member 13 for securing the upper portion 10 to the lower portion 11 and a helical expansion spring 14 interposed between the upper portion of the piston and the lower portion thereof.

20 The upper portion 10 of the piston is provided with a pair of spaced horizontally disposed opposite shelves 15, 16 intermediate its height which shelves are each provided with a transversely disposed slot 17, 18 and a screw threaded bolt shank 19 on which a nut 20 is adapted to be screw threaded secured, centrally depends from the interior of the upper portion of the piston, all as best shown in Figures 1, 5 and 6.

25 The upper portion 10 of the piston is provided with conventional compression and oil ring grooves 21, 22 respectively, the latter of which are each provided with oil ports 23 and the lower end of the upper portion of the piston has a depending hub 24 for centering the upper end of the helical expansion spring 14 when the several parts of the piston are secured together in their assembled relation.

30 The upper end of the lower portion 11 of the piston is provided with an upstanding hub 25 for centering the lower end of the helical expansion spring 14 when the several parts are secured together in their assembled relation and lower portion of the piston is preferably further provided with a plurality of vertically disposed oil draining ports 26.

35 The head 27 of the central connecting member 13 is provided with a bolt shank receiving aperture and the lower oppositely disposed sides 28, 29 are generally flared outwardly-downwardly and abut oppositely disposed shoulders 31, 32 inferiorly of the lower end of the lower portion 11 of the piston when the several parts of the piston are secured together in their assembled relation, all as best shown in Figures 4, 5 and 8.

40 55 The oppositely disposed sides 28, 29 of the cen-

tral connecting member 13 are each further provided with an aligned wrist pin slot 33, 34 within which the wrist pin 12 is adapted to vertically travel in instances wherein there is excessive combustion pressure on the upper surface of upper portion 10 of the piston and a plate 35 secured to the head 27 of the central connecting member as by spot welding and seated in the oppositely disposed slots 17, 18 of horizontally spaced shelves 15, 16 is provided with a bolt shank receiving aperture through which the bolt shank 19 is passed for securing the several parts of the piston together in the manner now to be described.

In securing the several parts of the piston in their assembled relation, the central connecting member 13 is first slid upwardly through the lower portion 11 of the piston until its oppositely disposed flared sides 29, 30 abut its oppositely disposed shoulders 31, 32.

The hub of the connecting rod, not shown, is next slid upwardly into the lower portion 11 of the piston and the wrist pin 12 is then passed therethrough and through the aligned oppositely disposed wrist pin slots 33, 34 after which the lower end of the helical expansion spring 14 is centered upon the upstanding hub 25 of the lower portion 11 of the piston.

The depending hub 24 of the upper portion 10 of the piston is next placed within the encircling upper portion of the helical expansion spring 14 which is thereupon compressed and the plate 35 secured to the head 27 of the central connecting member 13 is rotated from its position shown in dotted lines in Figure 6 to its position shown in full lines in the same view, seating the opposite ends thereof within the transversely disposed slots 17, 18 of the oppositely disposed shelves 15, 16 whereupon the lock nut 20 is threadedly secured to the bolt shank 19 to provide a rigid connection between the central connecting member 13 and the upper portion 10 of the piston under all operating conditions.

Combustion of the atomized fuel within the cylinder and above the head of the upper portion 10 of the piston, causes the upper end thereof to travel downwardly and any excessive combustion pressure on the head is taken up through the helical expansion spring 13 with no loss of power since the upper portion 10 of the piston will resume its normal position before the end of the power stroke, thereby preventing detonation and providing relatively higher compression ratios than are provided with conventional type pistons using standard grades of fuel.

Detonation which is caused by the sudden ignition of a charge of carbureted fuel within the cylinder during the sweeping of the flame across the combustion chamber, is precluded in the instant invention since pressure within the cylinder is not built up therein because of its expanding

combustion chamber. Thus the carbureted fuel burns gradually when ignited, resulting in complete combustion and the maximum utilization of the available energy.

5 It will thus be seen that the flexible piston herein shown and described is reasonably light in weight, highly efficient in use and is reasonably economical in manufacture and while but one specific embodiment of the invention has 10 been herein shown and described, it will be understood that certain details of the construction shown may be altered or omitted without departing from the spirit of the invention as the same is defined by the following claims.

15 I claim:

1. A piston for an internal combustion engine having an upper portion and a lower portion in spaced relation thereto having vertically spaced side walls whose lower ends are each provided 20 with a shoulder, a connecting member secured to the upper portion of the piston and limitedly slidably disposed within the lower portion thereof of whose lower ends are flared outwardly and are adapted to engage said shoulders, and a helical expansion spring interposed between the upper and lower portions of the piston.

2. A piston for an internal combustion engine having a hollow head portion and a lower portion in spaced relation thereto, the inner wall of 30 said hollow head portion having a pair of spaced shelves, each provided with a transverse slot, a connecting member limitedly slidably disposed relative to the lower portion and having a head portion seated within said slots, and a helical 35 expansion spring interposed between the hollow head portion and the lower portion of the piston.

3. A piston for an internal combustion engine having an upper portion and a lower portion in spaced relation thereto having vertically spaced side walls whose lower ends are each provided 40 with a shoulder, a connecting member secured to the upper portion of the piston and limitedly slidably disposed within the lower portion thereof of whose lower ends are flared outwardly and are adapted to engage said shoulders, and a helical expansion spring interposed between the upper and lower portions of the piston and encircling the limitedly slidably disposed member.

4. A piston for an internal combustion engine having a hollow head portion and a lower portion in spaced relation thereto, the inner wall of 50 said hollow head portion having a pair of spaced shelves, each provided with a transverse slot, a connecting member limitedly slidably disposed relative to the lower portion and having a head portion seated within said slots, and a helical 55 expansion spring interposed between the hollow head portion and the lower portion of the piston and encircling the limitedly slidably disposed member.

PHILIP S. WEBSTER.
